UNITED STATES PATENT OFFICE.

CHARLES MARTIN BAGSHAW, OF LEICESTER, ENGLAND, ASSIGNOR TO THE GIMSON SHOE MACHINERY CO. LIMITED, OF LEICESTER, ENGLAND, A CORPORATION OF GREAT BRITAIN.

PULLING-OVER MACHINE.

1,385,106.

Specification of Letters Patent. Patented July 19, 1921.

Application filed December 20, 1919. Serial No. 346,841.

To all whom it may concern:

Be it known that I, CHARLES MARTIN BAGSHAW, a subject of the King of Great Britain, of Leicester, in the county of Leicester, 5 England, have invented an Improvement in or Relating to Pulling-Over Machines, of which the following is a specification.

This invention relates to pulling-over machines employed in the manufacture of boots 10 and shoes and has reference to machines of the class wherein devices for gripping the upper are first actuated to stretch the upper about the last and are subsequently actuated to wipe-in the stretched upper which 15 is then fastened by means of tacks inserted automatically.

In machines of this kind the actuation of the gripping devices to wipe-in the stretched upper is performed by power-driven means. 20 The most important operation however, is the preliminary actuation of the grippers for stretching or setting the upper on the last. In some machines this actuation is effected by power-actuated means while in 25 others the grippers are moved by a treadle.

Now in connection with the pulling-over operation, various conditions arise when dealing with different classes of work, and it is recognized by those conversant with this 30 important process in boot and shoe manufacture, that while the preliminary stretch may be imparted in a certain way with advantage as far as some kinds of work are concerned, the same method is not suitable, 35 and moreover, may even be to some extent detrimental, in other kinds of work. For example, in dealing with the heavier class of work a preliminary stretch imparted by power-driven means may be an advantage 40 in so far that it relieves the operator of a considerable amount of labor and enables the pulling-over operation to be performed quickly. In dealing with the lighter class of work however, it is preferable that the 45 preliminary stretching operation shall be wholly or partly under the control of the operator in order that care may be exercised in obtaining a proper setting of the upper on the last, or that the preliminary stretch 50 may be imparted to that degree, which in the judgment of the operator, is necessary for each boot or shoe.

The present invention comprehends a pulling-over machine which will meet the various requirements as regards the impartation of the preliminary stretch when dealing with different classes of work. With such a machine the preliminary stretching or setting of the upper can be carried out in the manner most suited to the character of 55 the work.

According to this invention a pulling-over machine is constructed and arranged so that the movement of the upper gripping devices for stretching the upper may be effected partly by a treadle and partly by power-driven means, or wholly by a treadle, or wholly by power-driven means, the subsequent movement of the gripping devices for wiping-in the stretched upper being 60 65 70 brought about by power-driven means.

For example, according to one manner of using the machine, by operation of a treadle, the grippers may be closed upon the work and moved to any desired extent to 75 stretch the upper, the said treadle remaining unlocked during this operation so that the stretching effect is entirely under the control of the operator. The machine may then be started and caused to perform part of its 80 cycle, which completes the stretching mechanically, if the stretching has not already been wholly performed by the treadle operation. Upon this mechanical operation of the machine the treadle becomes locked when 85 the machine stops, the operator can inspect and, if necessary, adjust the upper. The machine is then again started and operates to wipe-in and tack the upper in the usual manner. In the above described preliminary stretching operation by treadle the operator can, by an appropriate operation of the treadle, either just close the grippers on to the upper, or he can stretch the upper 90 slightly over the last, or he can stretch it to 95 the full extent.

With the same arrangement, the machine may be used in another manner, viz., the whole of the preliminary stretching may be performed by power-driven means, in which 100 case, after the work has been placed in position, the machine is started and mechanically performs its first cycle to stretch the upper and then stops for inspection of the work

and upon being re-started completes the pulling-over by wiping-in and tacking the upper.

In both the above mentioned ways of using the machine, a further variation is possible by causing the machine, instead of operating with a two stage cycle, to complete the whole of its movement at once, *i. e.* instead of stopping for inspection of the work on completion of the stretching operation, it may be started to perform or complete the stretching operation and then immediately wipe-in and tack the work.

According to another manner of using the machine, the initial stretch may be imparted to a desired extent by actuation of the treadle which becomes locked in any position it may be moved to, and then the machine may be started to mechanically wipe-in and tack the upper. In this case the initial stretching of the upper is not influenced in any way by the power-actuated means, and the machine when started completes the whole of its cycle without stopping.

To enable the invention to be clearly understood reference will be made in the following further description to the accompanying drawings wherein an organized machine embodying the invention is shown by way of example.

In the drawings:—

Figure 1 is a side elevation of the machine.

Fig. 2 is an end elevation viewed from the right of Fig. 1.

Fig. 3 is a side elevation of part of the mechanism shown in Fig. 2 and is viewed from the right thereof.

Fig. 4 is a fragmentary view showing some of the parts of Fig. 2 arranged for a different operation of the machine.

Fig. 5 is a plan of the parts shown in Fig. 4.

Fig. 6 is a side view of some of the parts shown in Fig. 4 and is taken from the right of said figure.

Fig. 1 is drawn to a smaller scale than the other figures, and throughout the drawings like parts are designated by the same reference characters.

Referring to Figs. 1 and 2, the main frame 1 is attached to a base plate 2 which also carries an end standard 3. Mounted in bearings on the frame 1 and standard 3 is a clutch shaft 4 adapted to impart, through the pinion 5 and gear wheel 6 (Fig. 1), rotation to the machine shaft 7.

The grippers shown at 8 and 9 are connected by actuating coupling rods 10, 11 to a bracket 12 arranged to slide up and down in a guide 13 on the front of the frame 1. By means of links, one of which is shown at 14, the bracket is connected to a treadle 15 fulcrumed at 16 in the frame 1. By means of springs, one of which is indicated

at 17, the treadle is normally held in a raised position as shown, thereby, through the medium of the links 14, bracket 12 and couplings 10 and 11, holding the grippers in a raised and open position in readiness to receive the work.

A part 18 of the treadle extending rearwardly beyond the fulcrum 16 is connected by the members 19, 20, 21 and a toothed rack 22 (Figs. 1, 2 and 3) with a cam-operated lever 23 pivotally mounted at 24 on the main frame 1. The rod 19 is slideable in the socket 20 which is rigidly secured to the rod 21. The rod 19 and socket 20 are normally locked together by a spring-pressed bolt 50 (Fig. 1) straddled by a forked arm 51 of a bell-crank 52 connected by a rod 53 to an arm 54 fast with a hand-lever 55. When the telescopic parts 19, 20 are locked, the whole connection 19, 20, 21 is inextensible so that the treadle is operated by upward movement of the cam-operated lever 23, but if after such operation it is necessary to adjust the work, the hand-lever 55 is moved to cause the forked arm 51 to press against a collar 56 and withdraw the bolt 50 and thereby release the rod 19 from the socket 20, whereupon the grippers are raised by the springs 17. While these parts constitute a convenient form of connecting means it is to be understood that the present invention is not to be limited to such form as the operative connection between the treadle and the lever 23 and also the connection between said treadle and the grippers may be varied, it being understood that the connections are such that an actuation of the grippers will take place through the treadle from the lever 23.

The lever 23 is actuated by a cam 25 (Figs. 1, 2, 4, and 5) on the machine shaft 7 said cam engaging a roller 26 on the lever for this purpose. The clutch pulley 27 (Fig. 1) is driven by a belt in the usual manner and rotation of the shaft 4 is controlled by operation of the clutch member 28 this being effected by links 29 from a vertical slide 30 (Figs. 1 and 2) actuated by a connecting rod 31 and hand lever 32 the latter being fulcrumed at 33. The slide 30 is drawn down by springs 34 and in the normal, *i. e.* low position holds the clutch out of action. The machine shaft 7 has thereon a gapped disk 35 (Figs. 1, 2, and 4) the periphery of which engages a roller 36 on the slide 30 to hold the latter in the raised, *i. e.* operative position while the shaft 7 rotates.

The aforesaid toothed rack 22 which is combined with the lever 23 passes through a block 37 (Figs. 3 and 5) situated in the bifurcated end of the lever and mounted to turn upon two screws 38 as the lever rises and falls. Pivotally mounted at 39 on

the block 37 is a pawl 40 adapted to engage with the teeth of the rack 22 to lock the latter in the lever 23 for a purpose herein-after appearing. Fast with the pawl 40 is 5 a finger 41 which, when the lever 23 occupies a raised position as shown in Figs. 4, and 6, acts as a weight to hold the pawl 40 in engagement with the rack teeth, but which, upon the lever 23 descending, makes 10 contact with a stop 42 adjustably attached to the main frame 1 and is thereby moved as indicated in Fig. 3 to disengage the pawl 40 from the rack 22 to release the latter.

The rack 22 has formed therethrough a 15 hole 43 (Figs. 4 and 6) and the block 37 is provided with a hole 44. When by movement of the rack through the block the said holes 43 and 44 are brought into alignment, a pin 45 may be inserted as shown in Figs. 2, 3 20 and 5 to lock the rack and block this being required for certain operations of the machine as will be described later herein.

By reference to Figs. 2 and 4 it will be seen that the disk 35 is provided with two 25 gaps 46 and 47. For a certain operation of the machine the gap 46 may be rendered non-effective by the insertion of a filling-piece 48 (Fig. 4) therein.

The various methods of operation of the 30 machine made possible by the mechanical arrangements referred to will now be described.

According to one example the gap 46 in the disk 35 is left open as shown in Fig. 2 35 and the toothed rack 22 is fastened to the block 37 in the lever 23 by insertion of the pin 45. When the machine is in the normal position, the roller 36 is in the gap 46 and after the work has been placed in position, 40 the treadle 15 may be depressed by the operator to close the grippers 8, 9 upon the upper and move the grippers to any desired extent to stretch the upper. The depression of the treadle raises, by means of the 45 parts 18, 19, 20, 21 and 22, the lever 23 and thus according to the extent of such depression lifts the roller 26 from the cam 25.

Owing to the locking of the rack 22 to the block 37 by the pin 45, the treadle when 50 depressed as described remains unlocked and is therefore entirely under the control of the operator. Upon actuation of the hand lever 32 the machine is started and, providing the hand lever is released when the shaft 55 7 commences to rotate, the roller 36 will drop into the gap 47 and stop the machine after it has performed this part of its cycle. During the rotation of the shaft 7 just referred to, it will be observed by reference to 60 Fig. 2 that the rising part of the cam 25 passes under the roller 26 and that when the machine stops with the roller 36 in the gap 47 as shown in Fig. 4, the highest part 49 of the said cam will occupy a position under 65 the roller 26. It will therefore be under-

stood that if by a partial depression of the treadle 15 the lever 23 has been partly raised before the machine is started, the cam 25 will, as it rotates, pick up the roller 26 and complete the lifting of the lever 23. Or if 70 the treadle has not been depressed at all, the cam 25 will lift the lever entirely from normal position (Fig. 2) to the raised position (Fig. 4). Or on the other hand if the treadle has been depressed to such an extent 75 as to impart the whole of the stretch and fully raise the lever 23, then the cam 25 will rotate idly and its high part 49 will come into position under the roller 26 to hold up the lever and maintain the parts in 80 the stretching position when the machine stops.

Thus it will be seen that with the same setting of the machine the stretching may be imparted partially by the operator and finished by power, or it may be imparted wholly by power, or it may be imparted wholly by the operator. With either of the three methods just mentioned the machine may be allowed to stop after performing the 90 first part of its cycle, or alternatively, instead of stopping, it may, by holding the hand lever 32 depressed until the gap 47 has passed the roller 36, be caused to run on and perform the whole of its operation by a 95 single cycle.

With the arrangement or setting of the machine just described, the treadle, if depressed by the operator is not held mechanically or does not become locked in the depressed position until the machine has performed the first part of its cycle so as to bring the high part 49 of the cam 25 under the lever 23. Also in the arrangement referred to and by reason of the connection 100 between the lever 23 and rack 22, the treadle is moved to the same extent at each operation for stretching the work.

In another arrangement of the machine the pin 45 is withdrawn to release the 110 toothed rack 22, and the gap 46 is filled up by the piece 48 as shown in Fig. 4. In this case the normal position of the machine shaft 7 is that where the roller 36 occupies the gap 47 as shown, and in this position, 115 as already described, the lever 23 is held raised in its highest position by the high part 49 of the cam 25. The toothed rack 22 occupies a low position in the block 37 as shown in Fig. 6 when the treadle 15 and 120 the connected grippers are in the normal raised position.

After insertion of the work, the treadle is depressed by the operator to stretch the work to the extent desired and during such depression, the rack 22 is raised by the parts 125 18, 19, 20 and 21, through the block 37 and becomes locked against downward movement by the engagement of the pawl 40 with its teeth. Thus the treadle may be moved to a 130

greater or lesser extent as required by the work and is locked in whatever position it is moved to.

When after the stretching operation has been performed by the operator the machine is set in motion by actuation of the hand lever 32, the lever 23 already held up by the highest part of the cam 25 is not raised when the shaft 7 rotates and consequently no further stretch is mechanically imparted. The lever 23 remains raised while the concentric high part of the cam 25 passes under the roller 26 during which time the stretched upper is wiped-in and tacked. After this 15 operation and when the low part of the cam 25 passes under the roller 26, the lever 23 moves down, whereupon the finger 41 comes into contact with the stop 42 and disengages the pawl 40 from the rack 22. Upon the 20 release of the rack 22 the springs 17 controlling the treadle immediately act to return the treadle, grippers and rack to their normal position. As the gap 46 in the disk 35 is filled by the piece 48 the vertical slide 30 25 is not allowed to descend to stop the machine until the gap 47 comes into position under the roller 36. Therefore previously to the machine coming to rest the high part of the cam 25 passes under the roller 26 and 30 raises the lever 23 to the high position and the pawl 40 reengages the toothed rack 22 in readiness to lock the treadle upon depression of the latter at the next operation.

It may be convenient to connect the starting hand lever 32 to a second treadle (not shown) so that in some cases the machine may be started by an actuation of this treadle thus leaving the operator both his hands free to manipulate the work.

40 It will be understood that the actuation of the upper gripping devices for the purpose of wiping-in the stretched upper takes place mechanically by rotation of the machine shaft 7 after the upper has been stretched 45 in the manner hereinabove described, the present invention not being concerned with the particular mechanism for effecting such wiping-in movement. A full description of the pulling-over, wiping, and tacking mechanisms will be found in the specification of 50 United States Letters Patent No. 1293162 dated February 4th, 1919.

Claims:

1. A pulling-over machine having upper 55 gripping devices, a treadle to move said devices for stretching the upper, and power-driven means to move said devices for stretching the upper, said machine being constructed and arranged so that the movement of the upper gripping devices for stretching the upper may be effected partly by the treadle and partly by the power-driven means, or wholly by the treadle, or wholly by the power-driven means, for the 60 purpose described.

2. A pulling-over machine having upper gripping devices, a treadle and power-driven means to move said devices for stretching the upper, and power-driven means to move said devices for wiping-in the stretched upper, said machine being constructed and arranged so that the movement of the upper gripping devices for stretching the upper may be effected partly by the treadle and partly by the power-driven means, 70 or wholly by the treadle, or wholly by the power-driven means, said devices being subsequently moved for wiping-in the stretched upper, for the purpose described.

3. A pulling-over machine having upper 80 gripping devices, a treadle operable by the operator, connections between said treadle and gripping devices whereby the latter may be moved by the treadle for stretching the upper, power-driven means, connections between said power-driven means and the treadle whereby the latter may be actuated by the power-driven means, for stretching the upper, and means for controlling the operation of said power-driven means, the arrangement being such that the movement of the gripping devices for stretching the upper may be effected partly by the treadle and partly by the power-driven means, or wholly by the treadle, or wholly by the power-driven means, for the purpose described.

4. A pulling-over machine having in combination upper gripping devices, a treadle operable by the operator, connections between the treadle and the gripping devices for moving the latter to stretch the upper, power-driven means, connections between the power-driven means and the treadle to actuate the latter for stretching the upper, further power-driven means, and connections between same and the gripping devices for moving the latter to wipe-in the stretched upper, the treadle being operable independently of the power-driven means, for the purpose described.

5. A pulling-over machine having, in combination, upper gripping devices, a treadle operable by the operator, connections between the treadle and the gripping devices for moving the latter to stretch the upper, power-driven means, connections between the power-driven means and the treadle to actuate the latter for stretching the upper, further power-driven means, connections between same and the gripping devices for moving the latter to wipe-in the stretched upper, and manual means for controlling the operation of the power-driven means, for the purpose described.

6. A pulling-over machine having, in combination, upper gripping devices, a treadle operable by the operator, connections between the treadle and the gripping devices for moving the latter to stretch the upper,

power-driven means, connections between the power-driven means and the treadle to actuate the latter for stretching the upper, further power-driven means, connections between same and the gripping devices for moving the latter to wipe-in the stretched upper, manual means and automatic means for controlling the operation of the power-driven means, substantially as and for the purpose described.

7. A pulling-over machine having, in combination, upper gripping devices, a treadle operable by the operator, connections between the treadle and the gripping devices for moving the latter to stretch the upper, power-driven means, connections between said power-driven means and the treadle to actuate the latter for stretching the upper, the actuation of said treadle by the power-driven means being predetermined by the prior actuation of the treadle by the operator, means to control the operation of the power-driven means, and means to move the gripping devices for wiping-in the stretched upper, substantially as described.

8. A pulling-over machine having, in combination, upper gripping devices, a treadle operable by the operator, connections between the treadle and the gripping devices for moving the latter to stretch the upper, power-driven means, connections between said power-driven means and the treadle to actuate the latter for stretching the upper, further power-driven means for moving the gripping devices to wipe-in the stretched upper, means operating automatically to stop the machine after the action of the first mentioned power-driven means, and means operating automatically to stop the machine after the action of the second mentioned power-driven means, substantially as and for the purpose described.

9. A pulling-over machine having, in combination, upper gripping devices, a treadle operable by the operator, connections between the treadle and the gripping devices for moving the latter to stretch the upper, power-driven means, connections between said power-driven means and the treadle to actuate the latter for stretching the upper, further power-driven means for moving the gripping devices to wipe-in the stretched upper, means operating automatically to stop the machine after the actuation of the first mentioned power-driven means, and manually operable means to hold said automatic controlling means out of action for the purpose described.

10. A pulling-over machine having, in combination, upper gripping devices, a treadle operable by the operator, connections between the treadle and the gripping devices for moving the latter to stretch the upper, power-driven means, locking means,

and a device which renders the locking means inoperative and at the same time connects the treadle with the power-driven means so that it is actuated by the latter for stretching the upper, said device being removable to disconnect the treadle from the power-driven means and render the locking means operative so that they automatically lock the treadle when it is depressed by the operator to stretch the upper, substantially as and for the purpose described.

11. A pulling-over machine having, in combination, upper gripping devices, a treadle operable by the operator, connections between said treadle and the gripping devices for moving the latter to stretch the upper, power-driven means, locking means, a device which renders the locking means inoperative and at the same time connects the treadle with the power-driven means so that it is actuated by the latter for stretching the upper, said device being removable to disconnect the treadle from the power-driven means and render the locking means operative so that they automatically lock the treadle when it is depressed by the operator to stretch the upper, manually operable means to put the power-driven means into operation, and automatically acting means to control the operation of the power-driven means, substantially as and for the purpose described.

12. A pulling-over machine having, in combination, upper gripping devices, a treadle operable by the operator, connections between said treadle and the gripping devices for moving the latter to stretch the upper, power-driven means, locking means, a device which renders the locking means inoperative and at the same time connects the treadle with the power-driven means so that it is actuated by the latter for stretching the upper, said device being removable to disconnect the treadle from the power-driven means and render the locking means operative so that they automatically lock the treadle when it is depressed by the operator to stretch the upper, manually operable means to put the power-driven means into operation, automatically acting means to control the operation of the power-driven means, and means to adjust the said controlling means so that the machine is caused to operate with a two cycle movement or a single cycle movement, substantially as and for the purpose described.

13. A pulling-over machine having, in combination, upper gripping devices, a treadle operable by the operator to move said devices to stretch the upper, a driven cam, means to put same into action, a lever moved by said cam, and connections between said lever and the treadle whereby the latter is actuated by the cam, the arrangement being such that the treadle can be operated inde-

pendently of the cam, substantially as and for the purpose described.

14. A pulling-over machine having in combination, upper gripping devices, a treadle operable by the operator to move said devices to stretch the upper, a driven cam, a lever moved by said cam, connections between said lever and the treadle whereby the latter is actuated by the cam, a second cam, intermediate connections operated thereby to move the gripping devices to wipe-in the stretched upper, a gapped disk rotating in unison with the said cams, driving means, manually operable mechanism for

- 10 putting said driving means into operation, and means controlled by the gapped disk to put said driving means out of action, substantially as described.
- 15 15. A pulling-over machine having, in combination, upper gripping devices, an operable treadle and connections for moving said devices to stretch the upper, a driven cam, a lever moved by said cam, intermediate means between said lever and the treadle, a device to connect said lever with and disconnect it from said means so that the treadle is actuated by the driven cam or may be operated independently thereof, means for automatically controlling the rotation of the cam, and locking means combined with said lever and said intermediate means, said locking means being rendered respectively inoperative and operative by the aforesaid device when the latter effects connection and disconnection between the lever and intermediate means, substantially as and for the purpose described.

- 20 16. A pulling-over machine having, in combination, upper gripping devices, an operable treadle and connections for moving said devices to stretch the upper, a driven cam, means for automatically controlling the rotation of the cam, a lever moved by said cam, intermediate means between said lever and the treadle, pawl and rack locking means combined with the lever and intermediate means, and a device to effect connection and disconnection between the lever and intermediate means and simultaneously render the pawl and rack locking means inoperative and operative respectively so that the treadle is actuated by the cam or is operable independently thereof, substantially as and for the purpose described.
- 25 17. A pulling-over machine having, in combination, upper gripping devices, an operable treadle and connections for moving said devices to stretch the upper, a cam shaft, means to drive same, a cam on said shaft, a lever moved by said cam, intermediate means between said lever and the treadle, pawl and rack locking means combined with the lever and intermediate

connection between the lever and intermediate means and simultaneously render the pawl and rack locking means inoperative and operative respectively, a second cam on the shaft, connections operated by said second cam to move the gripping devices for wiping-in the stretched upper, a slide frame controlling the driving means, manually operable connections for moving said frame to start the machine, a roller on said frame, and a gapped disk on the cam shaft, said roller riding on said disk, substantially as and for the purpose described.

18. A pulling-over machine having, in combination, upper gripping devices, a treadle operable by the operator for moving said devices to stretch the upper, a driven cam, a lever moved by said cam, a pawl pivoted on said lever, a toothed rack slidable through the end of said lever and engaged by the pawl, connections between the rack and the treadle whereby the latter may be locked by the pawl after depression by the operator, a finger on the pawl, a stop with which said finger makes contact to disengage the pawl from the rack during movement of the lever, and a removable pin to lock the rack to the lever so that the pawl is rendered inoperative and the treadle is actuated by the lever, substantially as and for the purpose described.

19. A pulling-over machine having, in combination, upper gripping devices, a treadle operable by the operator for moving said devices to stretch the upper, a cam shaft, a clutch for driving the same, a cam on said shaft, a lever moved by said cam, intermediate means between said lever and the treadle, pawl and rack locking means combined with the lever and intermediate means, a device to effect connection and disconnection between the lever and intermediate means and simultaneously render the pawl and rack locking means inoperative and operative respectively, a second cam on the cam shaft, connections operable by said second cam to move the gripping devices for wiping-in the stretched upper, a slide frame, connections between said frame and the driving clutch, a manually operable member to move the frame in one direction to start the machine, springs to move said frame in the opposite direction to stop the machine, a roller on the frame, a gapped disk on the cam shaft with which the roller on the frame co-operates to effect stoppage of the machine at predetermined points in the cycle, and a removable filling piece for insertion into one of the gaps in the disk to render same inoperative and permit the machine to overrun the stopping place determined by said gap, substantially as and for the purpose described.

20. A pulling-over machine having upper gripping devices, a treadle operable by the operator to move said devices for stretching

the upper, power-driven means to actuate said treadle to stretch the upper, manually operable means to start said power-driven means, automatic means under the control 5 of the operator to stop the machine at the end of the power stretching operation, power-driven means for wiping-in and tacking the stretched upper, manually operable means to start said power-driven means, and automatic means to stop the machine at the 10 end of the tacking operation, substantially as and for the purpose described.

In testimony whereof, I have signed my name to this specification.

CHARLES MARTIN BAGSHAW.
